FULCRUM UNIT FOR DEDENTING LEVERS

Laurel M. Back, San Lorenzo, Calif.

Application January 19, 1956, Serial No. 39,849

Term of patent 14 years

(Cl. D54—13)

Figure 1 is a perspective view of a fulcrum unit for dedenting levers, embodying my new design.

Figure 2 is a plan view of the fulcrum unit.

Figure 3 is a perspective view of the fulcrum unit as seen from the end opposite that shown in Figure 1.

I claim:

The ornamental design for a fulcrum unit for dedenting levers, substantially as shown.
